UNITED STATES PATENT OFFICE.

ARTHUR RACINE, OF MONTREAL, QUEBEC, CANADA.

CAR-REPLACING APPARATUS.

1,378,132.

Specification of Letters Patent. Patented May 17, 1921.

Application filed June 17, 1919. Serial No. 304,858.

To all whom it may concern:

Be it known that I, ARTHUR RACINE, a subject of the King of Great Britain, residing at Montreal, Province of Quebec, 5 Canada, have invented certain new and useful Improvements in Car-Replacing Apparatus; and I do hereby declare that the following is a full, clear, and exact description of the invention, such as will enable others 10 skilled in the art to which it appertains to make and use the same.

This invention has relation to car replacing apparatus and more particularly appertains to the portable type used in connection with steam railroad cars, but the same 15 is also applicable for use in street car traction service, wherein the speedy replacing of the derailed car is necessary.

The primary object of the invention is to 20 provide replacing plates, which are readily positioned in proximity to the rails and afford means for elevating and consequently guiding the same back on the rails.

A further object of the invention provides 25 for the attachment of the devices to the rail ties either by spikes or the pressure exerted by the weight of the car thereupon.

A further object of the invention is to produce a device, upon use of which the wheels 30 are gradually guided and the stress encountered is equalized, thereby obviating the breaking of the plates or the consequent slipping of same.

With the above and other objects in view 35 which will hereinafter appear as the description continues, the invention consists of the novel features of construction, combination and formation of parts as will be hereinafter more fully described and particularly 40 pointed out in the appended claim.

In the accompanying drawings has been shown a simple and preferred form of the invention, it being, however, understood that no limitation is necessarily made to the precise structural details herein exhibited, but the right is hereby reserved to any changes, alterations or modifications to which recourse may be had that come within the scope of the claim without departing from 50 the spirit of the invention or sacrificing the efficiency of the same.

In the accompanying drawings:

Figure 1 is an elevational view showing the application of my invention to a freight 55 car, and a portion of the truck for same;

Fig. 2 is a plan view of one of the car replacing plates; and,

Fig. 3 is a side elevation of the same.

Referring now more particularly to the accompanying drawings wherein like and 60 corresponding parts are designated by similar reference characters throughout the several views.

Referring to the drawings, the numeral 1 designates a car replacing plate, which is 65 preferably constructed of steel and cast in one piece.

The replacing plates being two in number are of identical construction, being formed with a centrally disposed supporting pedestal 70 2 and wings 3. Reinforcement of the wings 3 is afforded by the downwardly projecting ribs 4 which connect the outer ends of the wings 3 with the supporting pedestal 2. The extreme outer ends 4' of the wings 3 75 are substantially flat, being disposed at an angle to the said pedestal and from these ends, the tread portion 5 on the upper face of plate 1, gradually rises to a point central of the pedestal, at which it attains its highest 80 elevation, and the said tread surfaces 5 begin at the flat outer ends 4', and as they gradually rise to the apex portion of the plates 1 indicated by 6, they likewise slant downward and inwardly at 7 from the outer marginal 85 edge toward the inner marginal edge of the plate.

As will be readily seen, this tread elevation is very gradual and likewise the angle of the downward projection at this point 90 extends even at a more gradual pitch than that attained during the above recited elevation.

A flange 8 is formed integral with the plate and extends along the entire outer 95 marginal edge of the plate, while the flanges 9 are formed integral with the inner marginal edge and extend only part of the way upwardly in the direction of the medial point of the plate. These flanges 9 are 100 spaced apart, and while they follow the elevation of the tread portion 5, they are disposed below the flange 8, the degree of inclination diminishing toward the center part of the plate as indicated at 6.

The application of my car replacing plates to the rails and ties is as follows:

The pedestal 2 as well as the flat ends 4' of the plates are formed with spurs 9' and have likewise openings for the reception of 110

bolts 10, by which the said plates may be attached to the ties, the weight of the car further forcing the spurs 9' inwardly in contact with the ties.

5 As will be seen, the plates 1 are placed in a position illustrated in Fig. 1, so that the inner flanges 9 engage the rail 11, the front wheels of the car will then ride upon the flat surfaces 4' of the plate ends, with the 10 flange 12 of one of the wheels engaging the plate flange 8, while the flange 13 of the other wheel will ride upon the tread surface 5 of the other plate 1, as the tread surface rises the wheels and their associated trucks 15 will be elevated and upon the approach of the wheels to the apex point of the plate, the latter are positioned in alinement with the rails and follow the downward incline of the tread surfaces from this point to the 20 flat surfaces 4' at the other end of the plates, and from thence on to the rails again.

By this construction the elevation and the resultant incline of the car is gradual and even stress is encountered by the plates.

25 When the plates are to be used for street car replacement work the spurs and bolts

may be dispensed with and the devices merely laid upon the road bed.

Having thus fully described my invention, what I claim as new and desire to secure by Letters Patent is:—

A car wheel replacing device, comprising a plate, the ends of which are disposed in a horizontal plane the said plate slanted upwardly from the horizontal ends formed in 35 central portion, vertical flanges extending upwardly from the inner edge of the plate and connecting the slanting portions with the horizontal ends, a rib formed on the outer edge of the plate and connecting the 40 slanting and horizontal portions, a single pedestal extending transversely of the central portion of the plate, with its lower edge flush with the lower side of the horizontal portions of the plate and a depending flange 45 formed upon the outer edge of the plate with its lower edge faced above the lower side of the horizontal ends of the plate and the said pedestal.

In witness whereof I have hereunto set 50 my hand.

ARTHUR RACINE.
